DESIGN FOR A ROCKING HORSE

Cecil G. Carlson, Hibbing, Minn.

Application November 10, 1944, Serial No. 116,269

Term of patent 3½ years

(Cl. D34—15)

To all whom it may concern:

Be it known that I, Cecil G. Carlson, a citizen of the United States and residing in the city of Hibbing, county of St. Louis, State of Minnesota, have invented a new, original, and ornamental Design for a Rocking Horse, of which the following is a specification, reference being made to the accompanying drawing, forming a part thereof, wherein:

Fig. 1 is a side perspective view of a rocking horse showing my new design;

Fig. 2 is a top plan view of the same; and

Fig. 3 is a front elevation of the same.

I claim:

The ornamental design for a rocking horse, substantially as shown.

CECIL G. CARLSON.
